ANGELO PURPURA, OF LAWRENCE, MASSACHUSETTS

SHOE INSOLE.

Application filed March 14, 1928. Serial No. 261,562.

This invention relates to an insole for a shoe, the general object of the invention being to so form the insole that it will act to correct various forms of foot trouble, such as swollen 5 arches, fallen arches, rheumatism in the feet, weak and flat feet and weakened arches, the device eliminating the use of arch supports which are awkward and cumbersome and difficult to properly position in a shoe, the 10 present device forming a part of the shoe.

This invention also consists in certain other features of construction and in the combination and arrangement of the several parts, to be hereinafter fully described, illustrated 15 in the accompanying drawings and specifically pointed out in the appended claim.

In describing my invention in detail, reference will be had to the accompanying drawings wherein like characters denote like or 20 corresponding parts throughout the several views, and in which:—

Figure 1 is a side view showing the improved insole placed in a shoe.

Figure 2 is a plan view of the insole.

Figure 3 is a section on line 3—3 of Figure 1.

Figure 4 is a section on line 4—4 of Figure 1.

Figure 5 is a section on line 5—5 of Figure 2.

As shown in Figure 1, the improved insole 1 forms a part of the shoe A. The insole has a small external flange 2 which extends from the center of the heel to a point just behind 35 the base of the fifth metatarsal bone and a large internal flange 3 which extends from a point adjacent the end of the heel to a point in close proximity to the base of the big toe and this flange extends upwardly to a point 40 well above the prominent bones on the inner side of the instep, the top of the flange terminating about half an inch below the malleolus. This flange 3 is curved to fit the instep at the inner side of the foot, as shown in the 45 drawings.

A projection 4 is formed on the central portion of the insole, this projection being of sub-

stantially wedge shape with its large rounded end located at the front adjacent the base of the toes and its small end terminating adjacent the front part of the heel. This projection is formed by a depression pressed into the under part of the insole. This depression will act against the inner cuneiform bones. The instep portion of the insole, with 50 the flanges and the projection 4 are hardened by the well known water process so that these portions of the insole will give a firm support to the parts of the foot engaged thereby. 55

Thus it will be seen that I have provided an insole for a shoe which takes the place of an arch support and forms part of the shoe and its use will correct flat feet, fallen and swollen arches, weak ankles, rheumatism of the feet, etc., and is a protection for the 65 astragalonavicular joint.

It is thought from the foregoing description that the advantages and novel features of my invention will be readily apparent.

It is to be understood that I may make 70 changes in the construction and in the combination and arrangement of the several parts, provided that such changes fall within the scope of the appended claim.

What I claim is:—

A shoe having its insole formed with an interior flange of small height and extending from a point at the center of the heel to a point just behind the base of the fifth metatarsal bone and an internal flange extending from a point adjacent the end of the heel to a point adjacent the base of the big toe, said inner flange being of curved shape in cross section and extending upwardly to a point slightly below the malleolus, a wedge-shaped 75 projection at the center of the insole with its large end rounded and located at the front end of the instep portion and its small end located a slight distance from the front portion of the heel, the instep portion of the insole, with the flanges and projection, being hardened. 80

In testimony whereof I affix my signature.
ANGELO PURPURA.
